Davis & Company, Detroit, Mich.

Filed Aug. 16, 1972, Ser. No. 281,070

Term of patent 14 years

Int. Cl. D24—01

U.S. Cl. D83—1 F

Fig. 1

Fig. 2

FIG. 1 is a perspective view of an electrocardiograph showing my new design;

FIG. 2 is a top plan view thereof;

FIG. 3 is a front elevation view thereof;

FIG. 4 is a side elevation view thereof; and

FIG. 5 is a rear elevation view thereof.

The chart paper extending over the side of the electrocardiograph shown in FIG. 1 is for illustrative purposes only. The side view not shown is a mirror image of FIG. 4.

I claim:

The ornamental design for an electrocardiograph, as shown and described.
